MAURICE ANDERSON, OF EDGEWOOD, RHODE ISLAND, ASSIGNOR TO LEVY, ANDERSON CO., INC., OF PROVIDENCE, RHODE ISLAND, A CORPORATION OF RHODE ISLAND

STRAP END ATTACHING DEVICE

Application filed February 23, 1929. Serial No 341,912.

This invention relates to a strap end attaching device for an extension device for a wrist watch strap or the like; and has for its object to provide a simple attachment for securing the extension device to the strap.

A still further object of the invention is the provision of a tip with resilient trunnions extending from its ends, the parts of which are formed of sheet metal.

With these and other objects in view, the invention consists of certain novel features of construction, as will be more fully described, and particularly pointed out in the appended claims.

In the accompanying drawings:

Fig. 1 is a top plan view of the device in unfolded position with portions of the strap attached thereto.

Fig. 2 is a view similar to Fig. 1 showing the parts of one of the sections further extended by sliding.

Fig. 3 is a bottom view partly in section of the parts shown in Fig. 1.

Fig. 4 is a perspective view of one end section.

Fig. 5 is a perspective view of the channel section or other end section.

Fig. 6 is a perspective view of one of the slidable parts of the intermediate section.

Fig. 7 is a perspective view of the other part of the intermediate section.

Fig. 8 is a sectional view of the device assembled and in folded position.

Fig. 9 is a sectional view on line 9—9 of Fig. 2.

Fig. 10 is a perspective view of the tip attached to the end of the strap.

Fig. 11 is a top plan view of the tip blank as formed from sheet stock.

Fig. 12 is a perspective view of one of the trunnions which is yieldingly extendible from the tip.

Fig. 13 is a sectional view thru the tip showing the trunnions in position.

Fig. 14 is a sectional view on line 14—14 of Fig. 3, showing the trunnions as engaging the side walls of the channel section.

In the use of wrist watch straps for securing wrist watches to the wrist of the wearer, it is found desirable to provide an extension

device which may provide an effective elongation of the strap for removing the same from the wrist of the wearer without detaching and separating any of the parts of the assembly; and in order to provide a maximum extension I have combined both the folding and subsequent sliding of the parts and so stiffened the sliding parts that they will not readily become bent or cramped to detrimentally affect their sliding action and at the same time I have used the stiffening means for limiting the movement of the parts one on the other and I have also formed a tip out of sheet metal with sheet metal trunnions yieldingly extending therefrom and engaging openings in the opposite side walls of the channel section to adjustably connect the same thereto; and the following is a detailed description of the present embodiment of this invention illustrating the preferred means by which these advantageous results may be accomplished:

With reference to the drawings, 15 designates one end section of the device formed with a pair of ears 16 to receive between them the tip 17 of the strap part 18 to connect the same thereto in a hinging relation. The opposite end section 19 is generally channel shape in cross section having a top 20, side walls 21 with a plurality of openings 22 therein for adjustment purposes hereinafter described.

An intermediate section is formed of two slidable parts 23 and 24 with the edges 25 of the part 23 rolled over the edges of the part 24 so that the parts are slidably held together. Ribs 26 are raised from the surface of part 24 which form corresponding depressions or grooves 27 having end walls 29 in the opposite surface of this section to receive 90 detents 28 cut and raised from the stock of the section 23 to extend into these spaced grooves 27 and guide and limit the sliding movement of the parts 23 and 24 one on the other by the engagement of the detents 28 95 contacting with the end walls 29 of the grooves which terminate short of the end of the section 24.

The part 24 of this intermediate section is hinged to the channeled or end section 19 by 100

means of trunnions 30 extending into openings 31 while the part 23 of the intermediate section is hinged to the opposite end section 15 by a pin 32 extending thru suitable hinge eyes 33 and 34 on the respective parts.

These sections may be folded one upon the other into the channel section 19 and held in folded position by the spaced portions 46 and 47 on the edge of the section 24 snapping beneath the tip 17, whereby the engagement is at spaced points adjacent the pivots to more firmly hold the parts in folded position. The top or channel section 19 is provided with a fingerpiece 53 to assist in unclaspings the parts to permit unfolding of the sections by a hinging action after which the slidable parts 23 and 24 of the intermediate section may be moved to further extend the effective length of the device.

20 The strap part 34 is adjustably connected to the channel section 19 by a tip 35 which is formed from a sheet stock blank, as illustrated in Fig. 11, folded to provide a part 37 for extending along one surface of the strap and a part 38 extending along the other surface of the strap, which parts are held in firm engagement therewith by means of fingers 36 which force the teeth 39 on the part 37 to bite into the strap 34 to assist in holding it against longitudinal strain and in a position such to space the fold 40 of the tip from the end 41 of the strap 34, in which space sheet metal trunnions 42 are housed and pressed outwardly by a spring 43 between their ends against stops 44 and 45 folded up from the part 38 of the tip.

In this manner a tip formed all of the sheet metal may be inexpensively constructed which is extremely thin and by which the resiliently mounted trunnions 42 may be adjustably secured to the differently spaced openings 22 in the channel section 19 for adjusting the effective length of the strap when in folded position.

45 It will be apparent that this tip may be used in connection with other constructions than the extension devices as here disclosed and it will be understood that a reference to an extension device so far as the tip is concerned is merely a reference for illustration purposes.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

30 1. A strap end attaching device comprising a sheet metal tip member folded upon itself to provide opposite side walls, means for binding it to one end of the strap with the fold spaced from said end of the strap, shouldered trunnions in said space for enter-

ing openings when forced outwardly, a spring between the said trunnions forcing them outwardly, and abutments bent up from the edges of only one of said walls and engaging the shoulders of said trunnions to limit their outward movement.

2. A strap end attaching device comprising a sheet metal tip folded upon itself to provide opposite side walls, fingers extending from the opposite edges of one folded part over the surface of the other folded part binding the tip to the end of the strap with the folded edge spaced from the end of the strap, shouldered sheet metal trunnions in said space for entering openings when forced outwardly, a spring between the said trunnions forcing them outwardly, and abutments bent up from the edges of only one of said walls of the tip to engage the shoulders of said trunnions and limit the outward movement of said trunnions.

In testimony whereof I affix my signature.
